UNITED STATES PATENT OFFICE.

GUSTAF ENGELBREKT, OF SUPERIOR, WISCONSIN; MARY ENGELBREKT, ADMINISTRATRIX OF SAID GUSTAF ENGELBREKT, DECEASED, ASSIGNOR OF ONE-FOURTH TO ERNEST A. BORGSTROM, ONE-FOURTH TO JOHN A. ANDERSON, AND ONE-FOURTH TO FRITZ HENDERSON, ALL OF SUPERIOR, WISCONSIN.

DRILL BIT AND LUBRICATOR.

1,404,016.

Specification of Letters Patent. Patented Jan. 17, 1922.

Application filed February 15, 1918. Serial No. 217,346.

To all whom it may concern:

Be it known that I, GUSTAF ENGELBREKT, a citizen of the United States, residing at Superior, in the county of Douglas and 5 State of Wisconsin, have invented certain new and useful Improvements in Drill Bits and Lubricators, of which the following is a specification.

The invention has for an object to present 10 a satisfactory appliance adapted to be attached to drills of various kinds to serve as an oil reservoir which will automatically feed a lubricant to the shank of the bit, in order to save the same from excessive 15 wear and damage. It is an important aim of the invention to give an appliance adapted to be used upon bits of the usual forms now in general use, without requiring special constructions of any kind in the bit stocks. 20 A further important aim is to enable the device to be produced in a simple form, to occupy but little space and to be applied and removed quickly to and from the drill bit.

25 Additional objects and advantages may appear from the construction and arrangement of parts hereinafter set forth and shown in the drawings, wherein,

Figure 1 is a longitudinal sectional view 30 of one form of the device applied to a bit,

Figure 2 is a cross sectional view of the device,

Figure 3 is a view of the device adapted to 35 bits with cylindrical shanks,

Figure 4 is a sectional view of a form of device including an oil reservoir.

There is illustrated a drill bit 10, which in the present instance is represented as having three grooves 11 therearound, the 40 drill shown in Figure 1 being represented as having a tapering shank 12 terminating in the rectangular tang 13, adapted to be engaged in a familiar form of drill chuck.

Upon the shank 12 there is engaged a 45 cup element 14, of approximately cylindrical form, having a thickened bottom portion 15, through which there is formed a concentric opening 16, the sides of which are fluted as at 17, forming a multiplicity of 50 small longitudinal passages when the opening 16 is fitted snugly upon the shank 12, these passages leading from within the cup 14. The opening 16 is of a diameter to

permit the cup to be adjusted upon the bit with a portion of the grooves 11 closely 55 thereadjacent or within the opening 16, as shown. The major diameter of the cup and the thickness of its wall is such that the annular space 17 around the shank 12 within the cup will readily accommodate packing material 18 loosely disposed therein. The packing may be varied or dispensed with, as desired. The outer end of the cup wall is interiorly threaded, and receives a gland 19, having a head 20 adapted to be 60 manipulated or engaged by a tool for rotation of the gland. The opening through the gland is of a size to permit it to fit loosely around the shank 12 when screwed into the cup as far as desired, as it is not 65 necessary for the cup to be held in exact concentric relation to the bit, and the gland is not depended upon for this purpose.

In the use of the device in this arrangement, the cup 14 is simply adjusted upon the 70 shank 12 and pressed toward the drill point until it becomes wedged at the thickest part of the shank, after which the cotton waste or other suitable material 18 is disposed within the cup around the bit shank 75 and liberally saturated with oil of a suitable character or the cup filled therewith. The gland 19 is then adjusted in the cup and screwed downwardly as far as necessary. When the bit is adjusted in vertical position, 80 the oil escaping through the passages formed by the fluting 17 moves downwardly upon the surfaces of the bit until it reaches the point, as will be readily understood. To renew the oil supply, it is simply necessary to 85 remove the gland 19 until it clears the upper part of the cup sufficiently to permit the insertion of an oil can spout, through which the oil may be replenished. When the drill is in operation, an occasional turn of the 90 gland 19 will insure the continued feeding of the lubricant in the proper quantity.

In Figure 3, the device is shown in a form that may be constructed approximately in the same shape as before described, and if 100 so desired, a spring element 25 may be mounted thereon to engage the shank of a cylindrical bit to prevent casual displacement of the device. In order to accommodate the clamping device, a kerf 26 is cut 105 in the bottom of the cup 14 which in the

present instance corresponds to the cup 14 first described, and a spring formed of wire adjusted with its intermediate portion extended through the kerf, while a pin 27 is inserted through the bottom portion of the cup and extending across the kerf. The lower part of the spring is formed with a coil 28, and a longitudinal arm 29 having an outwardly turned extremity, and adapted to bear against the shank 30 shown engaged in the device when the upper arm 31 of the spring is moved outwardly as shown, the device being thereby supported at such height on the drill bit as may be desired and the appliance made to accommodate shanks of different sizes. The arm 31 is disposed at such an angle to the arm 29 that when the former is at the inner limit of its movement closely adjacent the side of the cup 14', the arm 29 will project only slightly inward of the projected wall of the opening 32 through the bottom of the cup. The arm 31 is extended beyond the top of the cup and curved so that when the gland 20 is screwed into the cup it will engage the end of the arm 31 and bear it outwardly, causing a positive binding of the lower part of the device against the shank of the bit. In Figure 4 a method of forming the cup is illustrated, adapted to serve as a reservoir for a considerable quantity of lubricant, which may be found desirable upon bits used for making bores of considerable length. In this instance, the cup is in the shape of a bowl, the sides of which have the form of an ogee in cross section, the base of the bowl having an extension aperture to receive

a bit, while the upper part is enlarged laterally to give it ample capacity. The upper side of the bowl is formed with an opening 40 of considerable size, for convenience in manufacture, which is closed by a cap plate 34, suitably apertured at its center to receive the bit shank and provided at the longitudinal outward extension 35 by which it may 45 be rotated for emplacement or removal. In this form of the device the packing or other material may be loosely arranged in the lower part of the bowl, or omitted as found desirable, it being possible to close some of the grooves not registered with the grooves of the bit, leaving only a few others immediately adjacent the bit grooves open, through which oil may feed freely to the bit.

What is claimed:

A device of the character described comprising a cup element having an opening through its bottom adapted to receive slidably a bit shank, a spring element pivoted upon the cup having an arm extending therebelow and adapted to bear against a bit shank, and having an oppositely extended arm projected above the cup, and a gland element for the cup, said last named arm and gland being constructed to coengage 65 whereby the first named arm is borne inwardly to engage a bit when the gland is moved inwardly toward the cup.

In testimony whereof I have affixed my signature in presence of two witnesses.

GUSTAF ENGELBREKT.
